(57) **CLAIM**

The ornamental design for a container with surface indicia, as shown and described.

DESCRIPTION

FIG. 1 is a perspective view of a container with surface indicia, embodying our new design;

FIG. 2 is a front side view of the container with surface indicia of FIG. 1;

FIG. 3 is a first side view of the container with surface indicia of FIG. 1;

FIG. 4 is a back side view of the container with surface indicia of FIG. 1;

FIG. 5 is a second side view of the container with surface indicia of FIG. 1;

FIG. 6 is a top view of the container with surface indicia of FIG. 1; and,

FIG. 7 is a bottom view of the container with surface indicia of FIG. 1;

The broken lines shown in the drawings are for illustrative purposes only and form no part of the claimed design.
